UNITED STATES PATENT OFFICE.

CLYDE EASTMAN, OF THOMPSON FALLS, MONTANA TERRITORY.

WHEELED HAY-RAKE.

SPECIFICATION forming part of Letters Patent No. 349,837, dated September 28, 1886.

Application filed September 16, 1885. Serial No. 177,273. (No model.)

To all whom it may concern:

Be it known that I, CLYDE EASTMAN, a citizen of the United States, residing at Thompson Falls, in the county of Missoula, Montana Territory, have invented certain new and useful Improvements in Wheeled Hay-Rakes; and I do hereby declare the following to be a full, clear, and exact description of the invention, such as will enable others skilled in the art to 10 which it appertains to make and use the same.

My invention consists, first, in the combination, with an axle rake-head divided longitudinally and centrally, or nearly so, in a vertical plane from the end of one of its spindles 15 or arms to the end of its other spindle or arm, and having one or both of its respective halves grooved longitudinally on their flat sides and the rear half perforated, of rake-teeth passed through the perforated half, and having their 20 upper portions formed with retaining ends which stand at right angles, or nearly so, to their body portions, and are set in the longitudinal groove between the two halves of the axle rake-head and clamped firmly by means of 25 bolts and nuts or other suitable equivalent binding appliance; and, second, in a novel elevating and locking lever mechanism, in combination with the axle rake-head, said mechanism comprising a stop-standard, an upright 30 hand-lever fulcrumed upon a forward cross-bar of shafts hinged directly to the axle, two link-bars jointed together and forming a toggle-lever, and one of the link-bars being pivoted 35 to the hand-lever, and a nearly-circular lever pivoted to a rear cross-bar of the hinged shafts, and jointed to the rear link-bar of the toggle-lever and pivoted to the rear end of an eyebolt passed from the back through the axle 40 rake-head, as will be hereinafter described.

In the drawings illustrating my invention, Figure 1 is a perspective view of my improved rake. Fig. 2 is a vertical central longitudinal section of the same, showing the rake-teeth lifted from the ground. Fig. 3 is a similar 45 section, showing the rake-teeth held down upon the ground. Fig. 4 is a detail perspective view of a portion of the axle and a number of teeth attached thereto, the two halves of the axle being shown as moved apart. Fig. 5 is a detail view of a portion of the front half 50 of the axle and one rake-tooth. Fig. 6 is a

horizontal section of a portion of the axle rake-head and a number of teeth; and Fig. 7 is a detail view of a portion of a toggle-joint, whereby the rake-teeth are lifted or depressed. 55

In the drawings, A represents an axle rake-head; B, wheels at the ends of the axle rake-head; C, spring rake-teeth; D, shafts, and E driver's seat.

The axle rake-head A consists of two half- 60 axles, a a', united by transverse horizontal bolts a², so that they form a vertical central joint, a³, from end to end. In the line of this joint each half-axle rake-head is provided with a groove, a⁴, and when said halves are united 65 these grooves form a bed for the angular ends c of the rake-teeth C to lie in. Horizontal perforations a⁵ are provided in the rear half-axle rake-head, a, through which the rake-teeth pass, and in which they are held. At or 70 near the center of the axle rake-head a bolt, f, is passed through the axle rake-head halves a a', having a forked head, f', and a nut, f'', between which the axle rake-head halves are clamped together. (See Fig. 7.) To the forked 75 head f' a curved lever, F, is pivoted by means of a pin, f³, and this lever has a fulcrum, f⁴, on a cross-bar, d, of the shafts D, which are hinged to the axle rake-head A at a⁶. To the upper end of the lever F a link, g, is pivoted 80 at f', and this link is, by means of a pivot, g², connected to an arm, g³, of a hand-lever, G. This hand-lever is pivoted at g⁴ to an upright stand, d', fastened to a cross-bar, d², of the shafts D. The stand d' is provided with an 85 angular abutment, d³, by which the forward movement of the hand-lever G is limited. When the hand-lever G bears against the abutment d³, the connecting pivot g² is above a line struck from the pivot g' to g⁴, and thus 90 the rake-teeth C are locked or secured against incidental upward movement and kept down upon the ground to their work. In this position the driver can leave the hand-lever without keeping his hand on it, as long as the 95 rake-teeth are not required to be lifted.

If the rake is filled with hay, or if stones or stumps are in the way, the driver moves the hand-lever G backward, whereby the axle rake-head is revolved on the wheels B, and 100 the rake-teeth C are swung up from the ground, as shown in Fig. 2.

An ordinary driver's seat, E, is suitably fastened to the cross-bar d of the shafts D by means of a stand, e, of ordinary construction, and to the upper portion of this stand a bail, f^5 , 5 of an ordinary rake-tooth clearer, F', is hinged. The ends of the bail are fastened to a bar, f^6 , lying upon the rake-teeth in a position parallel to the axle rake-head A, and this bar f^6 is provided with teeth f^7 , which parts together 10 constitute the rake-tooth clearer. When the rake-teeth C are lifted from the ground, the bar f^6 slides along them toward their curved portions, so as to cause the teeth f^7 to discharge the gathered hay upon the ground.

15 Instead of having a groove, a^4 , in each half-axle, one of the half-axles may be provided with a similar groove, but deep enough to receive the angular ends c of the rake-teeth.

20 My construction of axle rake-head greatly simplifies the rake, renders the same durable and solid, and insures a very firm union between the teeth and the head, while convenience for removal of a broken tooth and the replacing of the same by a whole one is afforded, and the arrangement of the elevating and locking mechanism affords great convenience in operating the rake-head, and also insures a firm locking of the rake-teeth down to 25 their work.

25 I do not claim a divided rake-head set eccentrically with respect to undivided solid axle spindles or arms, and having clamped between its halves angularly-bent rake-teeth, as shown in Letters Patent No. 248,478, my invention differing therefrom in that I am enabled to 30 provide a divided tooth-clamping axle rake-head which is concentric with its spindles or arms, and is much simpler, cheaper, and more

durable and compact than rakes which have their heads set eccentrically upon spindles or 40 axle-arms; neither do I claim dumping mechanisms such as are shown in Patents Nos. 171,777 and 54,862, my dumping mechanism differing therefrom and comprising a very effective and novel combination of parts, whereby the axle rake-head is readily turned up to 45 discharge the gathered hay and positively held down when the raking operation is being performed.

What I claim as my invention is—

1. An axle rake-head divided longitudinally from the end of one of its spindles or arms to the end of its other spindle or arm in a vertical plane, and having a groove between its halves and perforations in the rear half, in 55 combination with rake-teeth having angular retaining ends and clamping-bolts or equivalents, substantially as and for the purpose described.

2. The combination, with an axle rake-head, 60 A, divided longitudinally through its spindles or arms, and having teeth clamped between its halves and turning up and down on said arms, of the rake-elevating mechanism comprising a stop - standard, $d^7 d^8$, on bar d^2 of hinged 65 shafts D, hand - lever G, arm g^3 , link g^4 , and curved lever F, fulcrumed on bar of said shafts and pivoted to the rear portion of bolt f of axle A, substantially as and for the purpose described.

In testimony whereof I affix my signature in presence of two witnesses.

CLYDE EASTMAN.
